HEISAKU HATAKEYAMA AND HOTORI WATANABE, OF KOBE, JAPAN

REFINING METHOD OF VEGETABLE OILS TO BE USED AS SOLVENTS FOR INJECTION MEDICINES

No Drawing. Application filed September 7, 1929, Serial No. 391,112, and in Japan September 12, 1928.

This invention relates to a refining method of vegetable oils to be used for medical purposes. It comprises removing glycerine and free fatty acids, the products of oil by decomposition, contained in the oil to be refined, and transforming free fatty acid which possibly remain in trace in the treated oil into an ester with aromatic alcohol. The object of this invention is to obtain a neutral solvent for oil-soluble substances to be used for hypodermic or muscular injection, which is never followed by irritation or pain.

Olive oil, for example, which has been used hitherto as a solvent of oil-soluble injecting medicine, such as camphor, has its acidity from 2 to 8 and its exponent of hydrogen-ion is from 2 to 4. It apparently contains glycerine and free fatty acid which have been produced by decomposition of oil. The exponent of hydrogen-ion of human blood being 7, the large difference of the number between olive oil and human blood as well as the presence of free fatty acid in the oil gives intolerable pain and the injected part often suppurates, if the injected medicine is dissolved in olive oil.

According to this invention, glycerine and free fatty acids contained in vegetable oil are at first removed as completely as possible, and a trace of free fatty acid that cannot be removed anyhow, is neutralized by transforming same into an ester with aromatic alcohol. In this way, the acidity of the treated oil becomes perfectly nil and its exponent of hydrogen-ion increases closely to 7. On account of these facts, if the oil refined in this way is used as a solvent of an injection medicine, the unfavorable effects above mentioned can be successfully avoided.

In this invention aromatic alcohols only are used to transform free fatty acid into an ester thereof. This is because:

1. Aromatic alcohols are esterified with free fatty acids easier than fatty alcohols. For example, olein acid and benzyl alcohol are easily esterified when they are slightly heated, while the acid and fatty alcohol are scarcely esterified without using a catalyst or a dehydrating agent as sulphuric acid or high pressure.

2. The ester made from an aromatic alcohol and a high grade fatty acid has local narcotic effect to human body, and when it is absorbed into human body it is easily oxidized and the excess of aromatic alcohol, if any, changes into harmless hippuric acid and is excreted. Contrary to this, the fatty acids with low molecular weight, such as ethyl or methyl alcohol, gives a great pain at the injected part, while the high-degree fatty acids such as butyl or amyl alcohol gives toxic effect to the central nerves when it is absorbed in human body.

The aromatic alcohols mean in this specification those which have OH group in side-chain of benzene ring, for example, benzyl alcohol

70

phenyl ethyl alcohol

75

cinnamic alcohol

80

oxybenzyl alcohol

85

which has OH groups in benzene ring as well as in side chain, and other oxyaromatic alcohols. These alcohols can be used in this invention, but mono and poly phenols with one or more OH groups in benzene ring should not be used, because these phenols have irritative and destructive effects to physical tissue.

This invention is further described referring to an example.

The vegetable oil to be treated should be decolored at first if it is colored one. Such decoloration can be easily attained by heat-

95

100

ing the oil to which a suitable quantity of acidic white clay and animal charcoal have been added. Two liters of such decolored oil is taken in a flask and is heated on water bath, to which is added 300 c. c. of distilled water at a temperature of about 100° C., and the mixture is shaken so as to make a homogeneous milky liquid. After it is maintained about half an hour at a temperature of from 50° to 60° C. it is poured into a separating funnel, where the mixture separates in 3 to 4 hours into two layers oil and water, whereupon the water layer is removed. This washing operation should be repeated several times till the removed water becomes non-acidic. In order to remove the water which closely mixes with the oil, red heated table salt of about 50 grams or other harmless dehydrating agent which is not soluble in oil is thrown in the oil, and the latter is filtered when it becomes transparent.

In spite of such a refining treatment, the concentration number of hydrogen-ion in the milky mixture of the refined oil with distilled water is 6.3 at the largest, and this number can never be increased how many times the washing operation is repeated. This means that a trace of free fatty acid still remains in the oil. Then 3% in volume of benzyl alcohol is added to the oil and is heated on water bath at a temperature of about 60° C. to 70° C. in order to esterify the free fatty acid. In order to remove the water produced due to esterification carbon-dioxide which has been dried by passing through sulphuric acid is bubbled in the oil. When the water is removed, the oil is heated under reduced pressure in order to remove excess benzyl alcohol which may remain in the oil.

The refined oil thus obtained is perfectly non-acidic, and the injection in which the oil is used as its solvent gives no pain at all, and there is no possibility of harming the injected part of the human body.

Claims:

1. A refining method of vegetable oils to be used as solvents for medical injection, which comprises removing the greater portion of glycerine and free fatty acid contained in the oil, and transforming free fatty acid which remain in trace in the oil into an ester by combination with an aromatic alcohol.
2. A refining method of vegetable oils to be used as solvents for medical injection, which comprises repeatedly washing the oil with water until the washed water is non-acidic, and adding thereto benzyl alcohol and heating same so as to make free fatty acid in the oil esterified.
